(57) **CLAIM**

The ornamental design for a manifold for flow switches, as shown and described.

DESCRIPTION

FIG. 1 shows a front view of a manifold for flow switches showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a top, front and right side perspective view thereof; and,

FIG. 8 is a partial cross-sectional view taken along line 8—8 of FIG. 7, but showing one end only.

The broken line showing of unclaimed portions forms no part of the claimed design.
